UNITED STATES PATENT OFFICE.

JOSEPH WALKER AND BRAINERD M. FREDERICK, OF SAN FRANCISCO,
CALIFORNIA.

TRUNK-PROTECTOR.

No. 836,227.

Specification of Letters Patent.

Patented Nov. 20, 1906.

Application filed March 28, 1906. Serial No. 308,394.

To all whom it may concern:

Be it known that we, JOSEPH WALKER and BRAINERD M. FREDERICK, citizens of the United States, residing at San Francisco, in the county of San Francisco and State of California, have invented certain new and useful Improvements in Trunk-Protectors, of which the following is a specification.

This invention relates to improvements in trunk-protectors, the object of the invention being to provide devices to be attached to the corners or edges of a trunk to protect the frame of the trunk from injurious shocks and jars and from twists and strains and to reduce the danger to the contents of the trunk; furthermore, to avoid cutting, scratching, scoring, or otherwise marring or disfiguring of trunks when one or more are piled upon others, one which will permit of the protective portion of the device being readily removed and replaced when worn out, and which will permit of the device being secured directly to the solid reinforced corners of the trunk instead of through the sides of the weaker portion of the structure.

In the accompanying drawings, Figure 1 is a perspective view of a trunk equipped with our improved devices. Fig. 2 is an enlarged perspective of one of the devices detached. Fig. 3 is a sectional view of the device. Fig. 4 is a sectional view of the casting, the rubber boss being removed. Fig. 5 is a sectional view of another form of the protector.

Referring to the drawings, 1 represents a holder, of brass or other suitable metal, having three inner surfaces each at right angles to the other two, and thus being adapted to fit snugly against the side, end, and bottom of a trunk. In the corner formed by said surfaces the holder is shaped to form a hollow threaded cylindrical extension 2, in which is contained a rubber boss 3, having a contracted thread portion 9 screwed within the extension 2 and having an annular shoulder 10 abutting against the circular edge of said extension. The inner surface of the contracted threaded portion of the boss is adapted to abut against the corner of the trunk and provides a protector therefor.

After the rubber boss is screwed into the extension it is firmly secured therein by means of screws 5, screwed through the side of the extension and into the boss. The holder

itself is secured to the trunk by means of 55 screws passed through screw-holes 4, said screw-holes being so arranged that the screws passing therethrough enter the sides and the bottom of the trunk at the ends and longitudinally therein, so as not to penetrate 60 any thin wood. In other words, the screws enter the sides and bottom of the trunk lengthwise instead of transversely. Moreover said screw-holes are so arranged that the screws through adjacent edges of the protector do 65 not interfere with each other in crossing.

In the modification of the invention shown in detail in Fig. 5 the casting 6 is provided with only two sides at right angles to each other, and adapted to be secured to two adjacent 70 surfaces of the box. In this case also there is provided a rubber boss 8, screwed into the casting and secured by the screws 7, said rubber boss also having the annular shoulder 10.

The rubber boss, having the annular shoulder and screwed into the threaded casting, permits of the protruding portions of the boss being made of sufficient size to afford protection to the trunk without unduly increasing the size of the metal holder 1. Moreover, 80 since the rubber boss enters the holder from the outside it can be detached and replaced at will, the holder remaining secured in its original position on the trunk, so that by supplying additional bosses to replace those 85 that are worn out the device can be used indefinitely. The portion of the boss entering the metal holder can be vulcanized to a greater degree than that on the outside, so as to render it firmer and more rigid and provide a more secure fastening in the holder, 90 while at the same time the exterior portion has greater resiliency.

We claim—

1. A trunk-protector comprising a metal 95 holder having holes by which it can be attached to a trunk, and having a hollow threaded extension, and a threaded rubber boss secured in said extension and having a shoulder abutting against the edge of the holder, substantially as described.

2. A trunk-protector comprising a metal 100 holder having holes by which it can be attached to a trunk, and having a hollow threaded extension, a threaded rubber boss 105 screwed in said extension and having a shoulder abutting against the edge of the holder, and a screw screwed laterally through said

metal holder into said rubber boss, substantially as described.

3. A trunk-protector comprising a metal holder having three sides arranged to lie closely against the sides of a trunk at a corner thereof and having a hollow threaded extension, said sides having holes by which the holder can be attached to the sides of the trunk, and a threaded rubber boss secured in said extension and having a shoulder abutting against the edge of the holder, substantially as described.

4. A trunk-protector comprising a metal holder having three sides arranged to lie closely against the sides of a trunk at a corner thereof and having a hollow threaded extension, said sides having holes by which the holder can be attached to the sides of the trunk, and a threaded rubber boss screwed into said extension and having a shoulder abutting against the edge of the holder, substantially as described.

5. A trunk-protector comprising a metal holder having three sides arranged to lie closely against the sides of a trunk at a corner thereof and having a hollow threaded extension, said sides having holes by which the holder can be attached to the sides of the

trunk, the holes in any side being sufficiently near the adjacent side that the screws or nails therethrough enter longitudinally or endwise the wooden side of the trunk against which said adjacent side lies, and a threaded rubber boss secured in said extension and having a shoulder abutting against the edge of the holder, substantially as described.

6. A trunk-protector comprising a metal holder having three sides arranged to lie closely against the sides of a trunk at a corner thereof and having a hollow threaded extension, said sides having holes by which the holder can be attached to the sides of the trunk, said holes in adjacent sides of the support being arranged so that screws therethrough pass each other, and a threaded rubber boss secured in said extension and having a shoulder abutting against the edge of the holder, substantially as described.

In witness whereof we have hereunto set our hands in the presence of two subscribing witnesses.
